ABSTRACT

A new and distinct *Calibrachoa* plant named 'INCALMIABE', characterized by its compact, upright to outwardly spreading and mounding to eventually trailing plant habit; vigorous growth habit; freely branching habit; dense and bushy appearance; early and freely flowering habit; apricot pink-colored flowers with yellow-colored throats; and good garden performance.

1 Drawing Sheet

1

Botanical designation: *Calibrachoa hybrida*.
Cultivar denomination: 'INCALMIABE'.

BACKGROUND OF THE INVENTION

The present invention relates to a new and distinct cultivar of *Calibrachoa* plant, botanically known as *Calibrachoa caesia* × *Calibrachoa hybrida* and hereinafter referred to by the name 'INCALMIABE'.

The new *Calibrachoa* plant is a product of a planned breeding program conducted by the Inventor in Heidesheim, Germany. The objective of the breeding program is to create new freely-branching *Calibrachoa* plants that flower early and freely with unique and attractive flower coloration and heat tolerance.

The new *Calibrachoa* plant originated from a cross-pollination conducted by the Inventor in Heidesheim, Germany in January, 2010 of *Calibrachoa* sp. 'USCALI28', disclosed in U.S. Plant Pat. No. 14,847, as the female, or seed, parent with a proprietary selection of *Calibrachoa* sp. identified as code number Ca10-1098-7, not patented, as the male, or pollen, parent. The new *Calibrachoa* plant was discovered and first selected by the Inventor as a single flowering plant within the progeny of the stated cross-pollination in a controlled greenhouse environment in Heidesheim, Germany in May, 2011.

Asexual reproduction of the new *Calibrachoa* plant by vegetative terminal cuttings in a controlled greenhouse environment in Heidesheim, Germany since August, 2013 has shown that the unique features of this new *Calibrachoa* plant are stable and reproduced true to type in successive generations.

2

SUMMARY OF THE INVENTION

Plants of the new *Calibrachoa* have not been observed under all possible combinations of environmental conditions and cultural practices. The phenotype may vary somewhat with variations in environmental conditions such as temperature and light intensity without, however, any variance in genotype.

The following traits have been repeatedly observed and are determined to be the unique characteristics of 'INCALMIABE'. These characteristics in combination distinguish 'INCALMIABE' as a new and distinct *Calibrachoa* plant:

- 15 1. Compact, upright to outwardly spreading and mounding to eventually trailing plant habit.
2. Vigorous growth habit.
3. Freely branching habit; dense and bushy appearance.
4. Early and freely flowering habit.
5. Apricot pink-colored flowers with yellow-colored throats.
6. Good garden performance.

The new *Calibrachoa* plant can be compared to plants of the female parent, 'USCALI28'. Plants of the new *Calibrachoa* differ primarily from plants of 'USCALI28' in the following characteristics:

- 25 1. Plants of the new *Calibrachoa* flower earlier than plants of 'USCALI28'.
2. Plants of the new *Calibrachoa* and 'USCALI28' differ in flower color as plants of 'USCALI28' have ruby red-colored flowers.

The new *Calibrachoa* plant can be compared to plants of the male parent selection. Plants of the new *Calibrachoa* differ primarily from plants of the male parent selection in the following characteristics:

1. Plants of the new *Calibrachoa* have larger flowers than plants of the male parent selection. 5

2. Plants of the new *Calibrachoa* and the male parent selection differ in flower color as plants of the male parent selection have red-colored flowers.

Plants of the new *Calibrachoa* can be compared to plants of the *Calibrachoa* sp. 'USCAL66501', disclosed in U.S. Plant Pat. No. 22,942. In side-by-side comparisons conducted in Bonsall, Calif., plants of the new *Calibrachoa* differed primarily from plants of 'USCAL66501' in the following characteristics: 10

1. Plants of the new *Calibrachoa* were more compact than plants of 'USCAL66501'. 15

2. Plants of the new *Calibrachoa* had smaller flowers than plants of 'USCAL66501'.

3. Plants of the new *Calibrachoa* and 'USCAL66501' differed in flower color as plants of 'USCAL66501' had coral red-colored flowers with greyed purple-colored centers. 20

Plants of the new *Calibrachoa* can also be compared to plants of the *Calibrachoa* sp. 'USCAL1411-12', disclosed in U.S. Plant Pat. No. 19,753. In side-by-side comparisons conducted in Bonsall, Calif., plants of the new *Calibrachoa* differed primarily from plants of 'USCAL1411-12' in the following characteristics: 25

1. Plants of the new *Calibrachoa* were more compact than plants of 'USCAL1411-12'. 30

2. Plants of the new *Calibrachoa* and 'USCAL1411-12' differed in flower color as plants of 'USCAL1411-12' had scarlet red-colored flowers. 35

BRIEF DESCRIPTION OF THE PHOTOGRAPHS

The accompanying colored photographs illustrate the overall appearance of the new *Calibrachoa* plant showing the colors as true as it is reasonably possible to obtain in colored reproductions of this type. Colors in the photographs may differ slightly from the color values cited in the detailed botanical description which accurately describe the colors of the new *Calibrachoa* plant.

The photograph at the bottom of the sheet is a side perspective view of a typical flowering plant of 'INCALMI-ABE' grown in a container. 45

The photograph at the top of the sheet is a close-up view of a typical flowering plant of 'INCALMIABE'. 50

DETAILED BOTANICAL DESCRIPTION

The aforementioned photographs and following observations, measurements and values describe plants grown during the summer in 10-cm containers in an outdoor nursery in Bonsall, Calif. During the production of the plants, day temperatures averaged 27° C., night temperatures averaged 18° C. and light levels ranged from 7,000 to 10,000 foot-candles. Plants were pinched two times and were six weeks old when the photographs and description were taken. In the following description, color references are made to The Royal Horticultural Society Colour Chart, 2007 Edition, except where general terms of ordinary dictionary significance are used. 55

Botanical classification: *Calibrachoa caesia*×*Calibrachoa hybrida* 'INCALMIABE'. 65

Parentage:

Female, or seed, parent.—*Calibrachoa* sp. 'USCALI28', disclosed in U.S. Plant Pat. No. 14,847.

Male, or pollen, parent.—Proprietary selection of *Calibrachoa hybrida* identified as code number Ca10-1098-7, not patented.

Propagation:

Type.—By vegetative terminal cuttings.

Time to initiate roots, summer.—About four days at day temperatures about 29° C. and night temperatures about 17° C.

Time to initiate roots, winter.—About six days at day temperatures about 21° C. and night temperatures about 17° C.

Time to produce a rooted plant, summer.—About 22 days at day temperatures about 29° C. and night temperatures about 17° C.

Time to produce a rooted plant, winter.—About 25 days at day temperatures about 21° C. and night temperatures about 17° C.

Root description.—Medium in thickness, fibrous; typically white in color, actual color of the roots is dependent on substrate composition, water quality, fertilizer type and formulation, substrate temperature and physiological age of roots.

Rooting habit.—Freely branching; medium density.

Plant description:

Plant and growth habit.—Compact, upright to outwardly spreading and mounding to eventually trailing plant habit; freely branching habit with about five primary lateral branches each with about four secondary branches; pinching enhances branching; dense and bushy appearance; vigorous growth habit.

Plant height.—About 11.9 cm.

Plant diameter.—About 12.4 cm.

Lateral branch description:

Length.—About 10.8 cm.

Diameter.—About 2 mm.

Internode length.—About 1.5 cm.

Strength.—Strong.

Aspect.—Initially upright then outwardly spreading to eventually trailing.

Texture.—Pubescent; minute.

Color.—Close to 146C.

Leaf description:

Arrangement.—Before flowering, alternate; after flowering, opposite; leaves simple.

Length.—About 3 cm.

Width.—About 1.3 cm.

Shape.—Elliptical.

Apex.—Rounded.

Base.—Attenuate.

Margin.—Entire.

Texture, upper and lower surfaces.—Pubescent; minute.

Luster, upper and lower surfaces.—Matte.

Venation pattern.—Pinnate; arcuate.

Color.—Developing leaves, upper and lower surfaces: Close to 146A. Fully expanded leaves, upper surface: Close to 146A; venation, close to 146B. Fully expanded leaves, lower surface: Close to 147B; venation, close to 147C.

Petioles.—Length: About 5 mm. Diameter: About 2 mm. Strength: Strong, flexible. Texture, upper and

lower surfaces: Pubescent; minute. Color, upper surface: Close to 146C. Color, lower surface: Close to 146D.

Flower description:

Flower type and flowering habit.—Single salverform flowers arising from leaf axils; freely flowering habit with typically about two to three open flowers per lateral branch and more than 70 flower buds and open flowers per plant at a time; flowers face upright to outwardly. 5

Fragrance.—None detected.

Natural flowering season.—Plants of the new *Calibrachoa* begin flowering about four weeks after planting; plants flower continuously from the early spring through the summer until the autumn in Southern California. 15

Flower longevity.—Individual flowers last about five days on the plant depending on ambient temperature; flowers persistent.

Flower buds.—Length: About 2.1 cm. Diameter: About 20 7 mm. Shape: Oblong, elongate. Color: Close to 160D.

Flower diameter.—About 2.5 cm by 2.8 cm.

Flower length (height).—About 2.5 cm.

Flower throat diameter.—About 6 mm by 9 mm. 25

Flower tube length.—About 1.8 cm.

Flower tube diameter, base.—About 2 mm.

Corolla.—Arrangement: Five fused petals in a single whorl opening into a flared trumpet. Petal lobe length (from throat): About 1.1 cm. Petal lobe width: About 1.4 cm. Petal shape: Fan-shaped. Petal apex: Rounded, slightly and shallowly emarginate. Petal margin: Entire. Petal texture, upper surface: Smooth, glabrous; velvety. Petal texture, lower surface: Pubescent; minute and primarily along the veins. 30 Throat texture: Smooth, glabrous. Tube texture: Pubescent; minute and primarily along the veins. Petal luster, upper and lower surfaces: Matte. Throat luster: Slightly shiny. Tube luster: Matte. Color: Petal lobe, when opening, upper surface: Close to 40 N170C to N170D. Petal lobe, when opening, lower surface: Close to 160D. Petal lobe, fully opened, upper surface: Close to 51A to 51B; towards the

10

25

35

40

throat, narrow band, about 1 mm in width, close to 46A; main veins, close to 47A; lateral venation, close to 51A to 51B; with development, color becoming closer to 185D. Petal lobe, fully opened, lower surface: Close to 54C; main veins, close to 185B; lateral venation, close to 54D. Throat: Close to 9A; venation, close to 183C. Tube: Close to 11C; venation, close to 183D.

Calyx.—Arrangement: One star-shaped calyx tube with five sepals fused towards the base and arranged in a single whorl. Sepal length: About 1 cm. Sepal width: About 2 mm. Sepal shape: Lanceolate. Sepal apex: Acute. Sepal margin: Entire. Sepal texture, upper and lower surfaces: Pubescent; minute. Sepal color, upper surface: Close to 146A. Sepal color, lower surface: Close to 146A to 146B.

Peduncles.—Length: About 1.6 cm. Diameter: About 1 mm. Angle: About 45° to 55° from stem axis. Strength: Strong. Texture: Pubescent; minute. Color: Close to 145A.

Reproductive organs.—Stamens: Quantity: Five per flower. Filament length: About 9 mm. Filament color: Close to 145C. Anther length: About 1 mm. Anther shape: Oval. Anther color: Close to 8B. Pollen amount: Scarce. Pollen color: Close to 8A. Pistils: Quantity: One per flower. Pistil length: About 1 cm. Style length: About 8 mm. Style color: Close to 145C. Stigma shape: Round. Stigma color: Close to 144B. Ovary color: Close to 145B. Seeds and fruits: Seed and fruit development have not been observed on plants of the new *Calibrachoa*.

Garden performance: Plants of the new *Calibrachoa* have been observed to have good garden performance and tolerate wind, rain and temperatures ranging from about 1° C. to about 40° C.

Pathogen & pest resistance: Plants of the new *Calibrachoa* have not been observed to be resistant to pathogens and pests common to *Calibrachoa* plants.

It is claimed:

1. A new and distinct *Calibrachoa* plant named 'INCALMIABE' as illustrated and described.
